MOUNT FOR ELECTRON TUBES

Otto H. Schade, West Caldwell, N. J., assignor to
 Radio Corporation of America, a corporation
 of Delaware

Application January 11, 1947, Serial No. 721,503

20 Claims. (Cl. 250—27.5)

1

The present invention relates to mounts for electron tubes and more specifically to heat radiating means incorporated in the structure of such mounts.

It is recognized that excessive heat developed within an electron tube can cause erratic operation of the device, resulting in loss of efficiency. For example, primary electron emission from the control grid may be one result of high thermal conditions within a tube causing unpredictable changes in the operating characteristics of the tube.

In some types of tubes, such as high permeance power tubes, such excessive heat may be a normal condition of operation. In recognition of this, some attempts have heretofore been made to dissipate the heat from the control grid. One way of accomplishing this has been to mount a heat radiator on the grid side rods. Such radiators have usually been mounted on the ends of the grid side rods extending through insulating spacers employed in the mount. While this is a satisfactory expedient in tubes where the elements do not require relatively close spacings and where the electrode assembly comprises a single unit structure, a serious problem is presented where the electrode spacings are relatively close and multiple electrode assembly units are involved.

Accordingly an object of my invention is to provide improved means for dissipating the heat generated in electron discharge devices during operation of such devices.

It is an additional object of my invention to provide a heat radiating structure for grids in multiple unit electron tubes.

It is a further object to provide heat radiators for grids in tubes wherein the electrodes are relatively closely spaced.

In certain types of tubes heat radiators employed to dissipate heat from the control grid are required to be of substantial surface areas in order to contribute to good operation of the device. In multiple unit tubes, where more than one grid is used, space accommodation for a plurality of such radiators presents serious difficulty. Moreover the relatively larger area of such radiators required in some tubes necessitates substantial extensions of the radiators laterally and axially of the mount. Such extensions present an additional problem of support. Usually tube mounts are supported at one end on the tube stem and at the other end by engagement with the side walls of the envelope of the tube. The pro-

2

vision of relatively large surfaced radiators on the end of the mount remote from the stem results in a mount structure extending above the support at said end and may contribute to vibration and distortion of the mount.

It is, therefore, a further object of the invention to provide a mount structure for an electron tube which includes a plurality of heat radiators constituting axial extensions of the mount and which is supported at the end remote from the stem against lateral forces.

An additional object is to provide a mount structure which includes a plurality of heat radiators of relatively large surface area at the end thereof remote from the stem which are free from interference with each other and which provide a support for said end of the mount.

A still further object is to incorporate heat radiators of good heat radiating properties in a multiple unit mount at one or both ends thereof without impairing the support function performed by the end of the mount remote from the stem.

Another object is to provide a plurality of heat radiators in a tube mount at least at one end thereof, having such shape that a relatively large radiating surface is provided on each radiator without physical or electrical interference occurring between the several radiators.

30. Further objects of my invention will become evident as the present description proceeds.

In the drawing to which reference is now made for a better understanding of the invention.

Figure 1 shows an elevation of a multi-unit type of electron tube using the novel mount of the invention;

Figure 2 shows an elevation of the same tube rotated axially through 90°;

Figure 3 is a section taken along the line 3—3 of Figure 1 and shows the shape and relationship to the mount of the upper heat radiators of the invention;

Figure 4 shows a section along the line 4—4 of Figure 1 and illustrates the shape and relation to the mount of the lower heat radiators of the invention;

Figure 5 is a transverse sectional view through 5—5 of Figure 1 and shows the electrode arrangement of the tube selected for illustrating the invention;

Figure 6 is a top view of the tube of Figure 1 with the envelope broken away and shows the rods employed for stiffening the mount and for supporting the getter;

55. Figure 7 is a perspective view of one of the

heat radiators employed in the upper part of the mount.

Figure 8 is a front view of one of the rods employed in my novel mount; and

Figure 9 is a side view partly in section of the rod shown in Figure 8 along the line 9-9 and illustrates an additional structural characteristic of the rod.

Referring now in more detail to the drawing there is shown in the figures thereof, various aspects of a double triode which includes my invention. It is not intended that the invention be limited to this type of tube, nor to the exact form shown since it will be apparent to persons skilled in the pertinent art that the invention may be embodied in many different types of tubes and may assume forms differing from the specific forms shown without departing from the scope thereof as pointed out in the appended claims.

Figures 1 and 2 show side views of an electron tube having an envelope 10 enclosing an electrode mount. The mount includes a stem 11 and an electrode assembly comprising two triode units, each unit including anode 12, grid 13 and cathode 14. The arrangement of these electrodes is best shown in Figure 5. Insulating spacers 15 and 16 engage end portions of the electrode assembly between opposite inner faces thereof.

It will be noted from Figures 3, 4 and 5 that the electrodes in the several units are relatively closely spaced. Furthermore the electrodes are relatively small in cross section, resulting in a relatively close spacing of the side rods 13a of the grids 13. In a tube of the type illustrated relatively high temperatures are produced during operation thereof. Grids 13 as a result may be subjected to temperatures at which they will emit primary electrons and thus disturb the efficiency of the tube. Primary electron emission from the grid caused by temperature conditions within a tube has long been the source of considerable difficulty in designing a tube for use under relatively high temperatures. In tubes where only one electrode assembly unit is utilized, this difficulty is to some extent overcome by providing cylindrical and other laterally closed metallic elements in heat transfer relation to the upper ends of the grid side rods. Such elements then dissipate heat by radiation. However, such radiation is limited to an appreciable degree to the outer surfaces of the closed elements. When such radiators are made small enough in cross section for use in heat transfer relation to the relatively closely spaced ends 13a of grids 13 of a double triode, their heat dissipating efficiency is below that required for good operation of the tube.

While the foregoing difficulties are associated with laterally closed heat radiators and suggest that such radiators are unsuited to the cramped space conditions in a multi-unit tube, a recourse to open sided or flat heat radiators contributes to even greater difficulty in solving the problem of adequate heat dissipation from grids in multi-unit tubes. Obviously flat radiators would require appreciably greater space accommodations than cylindrical or closed radiators for a given radiator efficiency. If such space requirements were met by longitudinal extensions of the radiators it would result in the need for a longer envelope of the tube. If the space requirement should be satisfied by laterally extending the radiators such extensions would interfere with other electrodes in the mount and with the extensions of adjacent radiators.

According to my invention heat radiators are provided which possess a novel cross sectional configuration rendering them suitable for side-by-side mounted relationship in an electron tube, and while physical interference between the radiators themselves and between radiators and other electrodes is eliminated, the heat radiating surfaces of the radiators are sufficiently large to contribute to good operation of the tube.

10 In Figure 7 one of the radiators 17 of my invention is shown. This radiator comprises a sheet metal body having a substantially planar portion 18 and an arcuate portion 19. The arcuate portion 19 preferably subtends an angle of substantially 90°. This radiator may be provided with a groove or a depression 20 on its planar portion to avoid contact with cathode 14 as shown in Figures 3 and 4. Surfaces adjacent the depression 20 are adapted to be welded to adjacent ends of grid side rods 13a.

15 In the illustrated embodiment of the invention two heat radiators of the type provided by my invention are mounted at each end of the electrode assembly of a double triode electrode tube and are disposed adjacent the exposed faces of insulating spacers 15-16. The radiators 17-17 of my invention, which are of like construction and dimensions, are mounted in the upper portion of the tube between insulating spacers 15-21. Radiators 22, 22, which are similar to radiators 17-17 in cross section but of shorter lengths, required for accommodation to the crowded conditions in the lower part of the tube, are disposed adjacent the exposed face of the lower insulating 20 spacer 16. The lower ends of radiators 22, 22 are free.

25 It will be noted from Figures 3 and 4 that the ends of grid side rods 13a projecting above the upper insulating spacer 16 are fixed to the planar surfaces 18, 18 of radiators 17, 17 in good heat transfer relation thereto. The planar surfaces 18-18 of radiators 17-17 extend towards the inner wall of envelope 10 and are bent adjacent the wall to form arcuate portions 19 which follow the curvature of the envelope 10 and are in proximity thereto. While the arcuate portion 19 of one of the radiators extends in one direction it will be noted that the arcuate portion of the other radiator extends in an opposite direction. 30 The arcuate extensions of the radiators do not, therefore, approach each other nor reduce the space between the radiators. The portions of the radiators that are closest spaced with respect to each other are the edges 23 thereof. The portions of the radiators which are farthest spaced from each other are the inner surfaces of the arcuate portions 19. This edge and surface relationship between the radiators 17-17 results in a minimum of interference between them in the performance of their heat dissipating functions as well as minimizing their interelectrode capacitance.

35 The absence of physical and functional interference between adjacent radiators of my invention is further contributed to by the unique construction of each of the radiators. To properly perform its function of dissipating heat from a grid, each of the heat radiators 17, 22 should be called upon to perform this function only. The radiator should not, for example, be called upon to dissipate heat that may be radiated to it by an adjacent radiator. The novel construction of my heat radiators effectively prevents any appreciable radiation of heat from one adjacent heat radiator to another. Thus the exposed face

of the planar portion of each of the radiators emits heat waves normal to its surface. This results in an unobstructed radiation of heat from this surface to the exterior of the tube. The outer face of the arcuate portion is also free to radiate heat waves to the exterior portion of the envelope without striking any intermediate element within the tube. The inner surfaces of the heat radiators also direct heat waves along a free path to the exterior of the tube envelope. Thus the heat rays emanating normally from the inner surface of the planar portion of each radiator strike the inner surface of the arcuate portion and are reflected in a direction substantially parallel to the planar surface. The heat waves that emanate from the inner surfaces of the arcuate portion of each radiator strike the inner surface of the planar portion and are reflected in a direction which includes a free path to the exterior of the tube envelope. The novel structure of my heat radiators, therefore, results in an efficient heat dissipation from the grids of the tube without physical or functional interference between adjacent radiators.

While the radiators of my invention have been described as including an arcuate portion 19, it is obvious that this portion may be planar and angularly disposed with respect to the planar portion 18 of the radiator. An arcuate shape is preferable, however, in connection with portion 19 of the radiator since this shape provides a larger surface area and greater mechanical strength than a planar portion would provide.

Radiators 17, 17 appearing in the upper part of the mount may be provided with any desirable longitudinal extension required for proper heat dissipation. It will be appreciated however, that a substantial longitudinal extension of the radiators 17 will necessitate a support at their free ends. Normally the electrode mount of the tube in question is supported against lateral forces at the end thereof remote from the stem 11 by means of insulating spacer plate 15. However, the mounting of heat radiators on the upper face of spacer 15 will result in an elongation of the mount beyond the point at which it is supported against lateral forces. If no additional support is provided at the upper ends of the radiators, it is possible that harmful vibrations may be set up in the mount, resulting in distortion in tube output. According to my invention, therefore, I provide a support at the upper ends of radiators 17. This support includes insulating spacer disc 21, which is provided with apertures through which suitable ears 23 of the radiators are adapted to extend. Metallic fingers 27 may be provided along the periphery of the spacer disc 21 to engage interior wall portions of the envelope 10.

Apertures are also provided in spacer 21 for permitting the passage therethrough of U-shaped rods 24. These U-shaped rods are most clearly shown in Figures 8 and 9. The legs of each of the U-shaped rods 24 are fixed to grooves 25 of a pair of anode elements 12, forming a part of each of the two triodes of the tube. The U-shaped rods are offset as at 26 to result in a fixed engagement between the U-shaped rods 24 and the spacer disc 21. This engagement supports the upper portion of the rods 24 against lateral movement and prevents axial displacement of the spacer disc 21 resulting in a stiffening of the mount.

In addition to performing a mount stiffening function, rods 24 are also adapted to support, adjacent their closed ends, getters 28. The sup-

port of the getters 28 at this portion of the mount results in an effective shielding of the electrodes thereof from any evolved getter material, the spacer 21 serving as an effective shield between the getter and the electrode assembly.

In addition to performing support functions in the mount the rods 24 also serve to connect the anode parts 12-12 of each anode electrically.

It is clearly to be understood that the invention is not limited to the specific embodiment illustrated, but that various modifications may be made therein, as will be apparent to persons skilled in the art, without departing from the scope of my invention as pointed out in the appended claims.

I claim:

1. A mount for an electron tube of the multi-unit type including independent control grids having side rods lying in a common plane and coextensive with each other, and heat radiators connected to adjacent ends of said rods, said heat radiators comprising sheet metal bodies having two surface portions, one of said surface portions being substantially planar and extending between two of said side rods of one of said grids and the other of said surface portions being arcuate and extending from one edge of said planar portion.
2. A mount for an electron tube having a plurality of electrode systems including control grids, the elements of each of said systems being relatively closely spaced and a heat radiator connected to each of said grids at a predetermined end thereof, said heat radiator having a surface of substantial area, a portion of said surface extending radially of said mount and an additional portion of said surface of arcuate cross section having a center of curvature concentrically disposed with respect to said mount.
3. An electron tube having an envelope and a mount provided with a stem, said mount including a plurality of electrode systems including control grids, two insulating spacers between which said electrode systems are supported, portions of said control grids extending through said spacers and projecting from the outer surfaces thereof, one of said spacers being more remote from the stem of said tube than the other of said spacers, heat radiators mounted on the outer face of the more remote of said spacers, each of said heat radiators being connected to the projecting portion of one of said control grids, said radiators having edges disposed adjacent the outer face of said more remote spacer, and additional edges displaced from and parallel to said first-named edges, an insulating plate engaging and fixed to said additional edges, and means on said insulating plate for engaging a portion of the inner walls of said envelope whereby said mount is supported at the end thereof remote from the stem against lateral forces.
4. A mount for an electron tube comprising a plurality of electrode systems, two insulating spacers engaging opposite ends of said electrode systems and having inner and outer faces with respect to said systems, one of said spacers being more remote than the other from the stem of the mount, heat radiators for said systems supported on the outer face of said more remote of said spacers, each of said radiators being connected to an electrode of one of said systems, each of said radiators having a planar surface portion extending radially of said mount and an additional surface portion extending angularly from said first-named portion, whereby said radiators

are provided with relatively large surface areas which are free from physical and electrical interference with each other, and an insulating plate engaging the ends of said radiators remote from said outer face of said more remote spacer for supporting the mount against lateral forces.

5. A mount for an electron tube comprising a plurality of electrode systems, two insulating spacers engaging opposite ends of said systems and having inner and outer faces with respect to said systems, one of said spacers being more remote than the other from the stem of said mount, and heat radiators for said systems supported on the outer face of said spacers, each of said radiators being connected to an electrode of one of said systems, a third insulating spacer facing said one of said spacers, one edge of two of said radiators engaging said outer face of said other of said spacers and the inner face of said third spacer, said radiators having all surfaces lying in planes parallel to the longitudinal axis of the mount, one portion of each of said radiators being planar and extending radially of the mount and the other portion thereof being angularly disposed with respect to said first-named portion.

6. A mount for an electron tube comprising an electrode assembly having a plurality of units, including control grids, said control grids having adjacent end portions, heat radiators connected to said end portions, each of said radiators comprising a planar surface portion and an additional surface portion angularly disposed with respect to said planar surface portion, said additional surface portion in adjacent radiators extending in substantially opposite directions whereby a relatively large surface area is provided for each of said radiators without causing physical interference between adjacent radiators.

7. An electron tube comprising an envelope and a mount enclosed thereby, said mount including a plurality of electrode systems, each of said systems having a plurality of electrodes, said systems and said electrodes being relatively closely spaced, heat radiators for two analogous electrodes in said system made of sheet metal of substantial surface area, said heat radiators being mounted on end portions of said two analogous electrodes, each of said radiators including a substantially planar portion extending towards the adjacent wall of said envelope, and an additional portion angularly extending from said first-named portion adjacent said wall transversely of said mount.

8. An electron tube comprising an envelope and a mount enclosed thereby, said mount including a plurality of electrode systems, each of said systems having a plurality of electrodes, said systems and said electrodes being relatively closely spaced, heat radiators for said electrodes made of sheet metal of substantial surface area, said heat radiators being mounted on end portions of said electrodes and including substantially planar portions extending towards the adjacent wall of said envelope, and additional portions angularly extending from said first-named portions adjacent said wall transversely of said mount, said heat radiators forming an end portion of the mount remote from the stem thereof, and means on the free end of said end portion engaging the inner wall of said envelope for supporting said mount against lateral forces.

9. A mount for an electron tube including a heat radiator comprising a sheet metal body having a substantially planar surface portion lying in a plane which includes the longitudinal axis of

the mount and an additional surface portion extending angularly from said first-named portion, an electrode in said mount, said heat radiator being connected to an end portion of said electrode, whereby said heat radiator is provided with a relatively large surface area for efficient heat dissipation from said electrode, and means for supporting said heat radiator independently of said electrode.

10. An electron tube of the multiple unit type having an envelope, at least two control grids in said tube, said grids having side rods lying in a common plane and coextensive with each other, heat radiators for said grids, said heat radiators being mounted on end portions of said side rods in heat transfer relation thereto, each of said heat radiators including a planar surface portion and an additional surface portion angularly disposed with respect to said planar surface portion, said planar portion extending towards a side wall of said envelope, said additional surface portion extending from said planar surface portion adjacent said side wall whereby each of said radiators has a relatively large surface area and adjacent radiators are free from physical and have small electrical interference with respect to each other and with respect to the other electrodes of the tube.

11. An electron tube comprising an envelope and a mount enclosed thereby, said mount including at least two electrodes for operation at relatively low temperatures, said electrodes being parallel and in registering relationship, end portions of said electrodes lying in a common plane, heat radiators having relatively large surface areas fixed to said end portions, said heat radiators comprising sheet metal bodies and being in spaced edge relationship at portions thereof in closest proximity and in spaced surface relationship at portions thereof farther removed from each other.

12. An electron tube having an envelope and a mount enclosed thereby, means in said mount defining at least two cylindrical spaces, an electrode assembly supported in one of said spaces, said means being located at one end of said assembly, electrodes in said assembly requiring lower operating temperatures than the temperatures in said one of said spaces, and heat radiators in the other of said spaces in heat transfer relation with said electrodes, said radiators being made of sheet metal and having portions thereof partly defining an enclosure in said other of said spaces, other portions of said radiators having edges longitudinally of said mount and oppositely disposed.

13. An electron tube having an envelope and a mount enclosed thereby, means in said mount defining at least two cylindrical spaces, an electrode assembly supported in one of said spaces, said means being located at one end of said assembly, electrodes in said assembly requiring lower operating temperatures than the temperatures in said one of said spaces, heat radiators in the other of said spaces in heat transfer relation with said electrodes, said radiators being made of sheet metal and having portions thereof partly defining an enclosure in said other of said spaces, other portions of said radiators having edges in spaced faced relationship and extending longitudinally of said mount, and means extending into one of said spaces and fixed to another electrode therein, said means traversing said other of said spaces and extending beyond the same to stiffen said mount against lateral forces.

14. A mount for an electron tube including in combination at least two heat radiators of sheet metal body, a portion of each of said radiators forming part of a cylindrical wall concentric with said mount, another portion of each of said radiators extending from said first-named portion toward the axis of the mount, and electrodes in said mount requiring heat dissipation, each of said radiators being connected to an end of one of said electrodes.

15. An electron tube having a pair of adjacent sheet metal radiators and including two electrodes having end portions connected to said radiators, said radiators extending axially of said tube and each including a surface portion extending radially of said tube and connected to one of said electrodes, an additional surface portion of each of said radiators extending parallel to the side walls of said tube, said additional surface portion of one of said radiators extending in the same rotary direction as said additional surface portion of the other of said radiators.

16. A mount for an electron tube having a pair of adjacent sheet metal heat radiators, portions of said radiators forming parts of a cylindrical wall concentric with said mount, other portions of said radiators extending from said first-named portions thereof toward the longitudinal axis of said mount, said first-named portions being oppositely disposed, said last-named portions lying substantially on a diameter of said mount, and being more closely spaced with respect to each other than said first-named portions, and electrodes in said mount connected to said radiators at said last-named portions thereof, whereby radiators of substantial heat dissipating property are provided in a relatively small space.

17. An electron discharge device having an electrode mount including a grid having a pair of oppositely disposed side rods, a radiator for said grid including a sheet metal element having a substantially planar portion secured to one end of said side rods and extending parallel to said side rods, and an arcuate shaped portion extending from one end of said planar portion transversely of said mount, all flat surfaces of said radiator being parallel to the longitudinal axis of said mount.

18. An electron discharge device having an

electrode mount, an electrode assembly in said mount, a pair of insulating spacers defining extremities of said electrode assembly, at least one heat radiator supported axially of the mount, and a pair of insulating spacers for said radiator, one of said insulating spacers being common to said electrode assembly and said radiator.

19. An electron discharge device having an envelope and a mount enclosed thereby, three parallel insulating spacers displaced axially of said mount, said mount including a stem, an electrode assembly, and at least one heat radiator for one of the electrodes in said assembly, said electrode assembly being supported between two of said spacers, said radiator being supported between two of said spacers, said last-named spacers including the spacer most remote from said stem, spring finger spacers on said spacer for engaging inner walls of said envelope whereby said mount is supported against lateral forces at the end thereof remote from said stem.

20. A mount for an electron tube including two oppositely disposed heat radiators of sheet metal, said radiators including substantially planar surface portions extending along a diameter of said mount and separated at the center of said mount, and arcuate surface portions extending from said planar portions at the ends thereof remote from said center of the mount, the arcuate surface portion of one of said radiators extending in one direction to include substantially a quadrant of the periphery of said mount, and the arcuate surface portion of the other of said radiators extending in a direction opposite to said one direction to include substantially another quadrant of said periphery, whereby the inner and outer surfaces of said radiators are substantially free to serve as heat radiating surfaces.
